UNITED STATES PATENT OFFICE.

CHRISTOPHER WILKE, OF SEATTLE, WASHINGTON, ASSIGNOR OF FORTY-NINE PER CENT TO ROY TAYLOR, OF SEATTLE, WASHINGTON.

WINDOW VENTILATOR.

Application filed May 22, 1924. Serial No. 715,031.

To all whom it may concern:

Be it known that I, CHRISTOPHER WILKE, a citizen of the United States of America, and resident of the city of Seattle, in the 5 county of King and State of Washington, have invented certain new and useful Improvements in Window Ventilators, of which the following is a specification.

My invention relates to window 10 ventilators of that type which employ a frame insertible into the casing of a window and which serve as deflectors to direct the incoming air upwardly to thereby avoid drafts acting upon the occupants of a room.

15 The object of my invention is to provide a simple and convenient construction of this kind which will permit of free raising and lowering of the windows within certain limits, but which when in place will provide a secure closure preventing the window being raised above a predetermined level and preventing any access to the room through the window.

20 Other objects of my invention may be determined from a study of the following description and the drawings accompanying the same.

25 The features of my invention which I desire to protect by a patent will be defined by the claims terminating this specification.

30 The accompanying drawings show my invention in the form of construction which I now prefer to use.

35 Figure 1 is a transverse sectional view, the line of section being through the median portion of the device and the window sash.

40 Figure 2 is a top plan view showing one end of my device, with the window sash and casing in section.

45 Figure 3 is a section showing in detail the construction of my device taken on the line 3-3 of Figure 2, the plane of section being just inside of the casing.

50 The frame of my device is of triangular cross section. It is designed that this frame shall be of such a width in the general plane of the window, as to snugly fill the space between the window casing. The vertical face of the frame is placed parallel with and close to the window sash. The opposite face inclines into the room and upwardly, thus forming a plate for deflecting the incoming air upwardly. The end walls or

sides are of triangular outline. The details of construction of the frame proper may be varied as desired and found suitable.

The frame has, among its chief members, 60 a bottom bar 2 which is designed to rest upon the window sill 12. Also two end walls of triangular shape are provided, with the apex of the triangle downward. A transversely extending bar 21 is located at 65 the upper inner corner of the frame and connects the two end walls. These walls are preferably further connected by a tie rod 43 or some equivalent construction. The rod 43 as illustrated is located close to 70 the window and near the upper edge of the end walls 4.

The main body of the inner inclined wall which forms the air deflector, is preferably composed of a plate 20 of glass, suitably 75 mounted in the body of the device acting as a frame. This glass also serves as a stop for any rain which may drive through the window when open. Such rain, running to the bottom of the glass, will be discharged 80 outside the window sill 12. To insure free discharge of such water either the lower bar 30 of the screen frame, or the lower bar 2 of the main frame of the device, should be provided with transverse grooves as 31 to 85 permit free discharge of the water.

The vertical outer face of the ventilator frame is provided with a screen 3, and the vertical side edges of this screen are mounted to slide in grooves 40 formed in 90 the end walls 4. The screen, is however, normally held down so that it may not be raised, by a bar 5, which extends between the end walls 4 and which is held down in fixed position by some suitable means. The 95 construction illustrated provides a downwardly extending lug 50 carried by the bar 5 which enters and fills a groove 41 extending transversely across the upper edge of the end wall, which groove may, and preferably, is aligned with the screen-receiving groove 40. This prevents side movement of the stop bar 5 and thus prevents its displacement in one direction. The means employed for holding the bar 5 down upon 100 the top of the screen may vary. That illustrated consists of a spring bar 6 secured by its lower end to the outer face of the end wall 4 and provides at its upper end with a lateral offset 60 adapted to snugly engage 110

with the upper surface of the bar 5, as has been illustrated in Figure 3. This spring should have sufficient resiliency as to permit of its being displaced endwise of the bar 5 sufficient to permit raising of the bar.

The outer side edge of the bar 5, that is the edge which is towards the window sash, projects to a point where it is very close to the glass pane 11 of the sash. It is, therefore, in position to engage the lower bar 10 of the window sash and prevent its being raised above this point. This makes it possible to leave the sash in raised position, which otherwise might not be safe and would permit the entrance of burglars, without there being any chance of such entrance. The bar 5 securely holds down the screen 3 and prevents raising of this sufficient to insert a hand. While, of course, the screen 3 might be cut, yet the device as a whole is so secured as to make it difficult for unlawful entry.

The means which I prefer to employ for securing the device to the window casing, consists of two ordinary door bolts. One of these is shown in Figure 2. The main frame of this bolt is secured to the inner face of the casing, while the sliding bolt enters a keeper 70 which is secured to the outer face of the end wall 4. Another bolt 7 of the same character is provided on the opposite end of the device. This being located at about the middle of the height of the device, places it out of reach of any one who might endeavor to reach it from the outside.

To accommodate the window shade 8. I provide the upper edge of the side walls 4 with a groove 42, into which the bar 80 at the lower edge of the shade may enter. This is located close up to the inner face of the screen so that wind entering the opened window, when this device is in place will not be apt to blow the shade about. Unless the lower end of the shade were held close to the screen, wind entering the ventilator would blow the shade about, causing noisy flapping and injuring the shade.

This device, being secured in place by two ordinary door bolts 7, makes it possible to secure it in place and remove it very quickly. When in place and the window raised, the access of air to the room is possible without the entrance of rain and also without the probability of unwarranted entrance by prowlers. The whole device is simple and may be manufactured at a very reasonable cost. Being provided with glass, 20, it does not materially shut out the light.

What I claim as my invention is:

1. A window ventilating device comprising a frame adapted to be secured within a window casing and having an inclined air deflecting inner wall, side walls and a screen

forming the vertical outer wall, said side walls having guiding grooves for holding the side edges of the screen and opening freely at their upper ends to permit upward removal of the screen, a bar extending along the top edge of the screen and having interlocking engagement with the frame sides and also having its outermost edge projecting to prevent the window sash being raised above it.

2. A window ventilating device comprising a box-like frame adapted to be placed in a window opening against the inner face of the sash, said frame having side walls adapted to fit against the casing faces at the sides of the window opening and having vertical screen-receiving guides located close to the inner face of the sash, a screen slideable in said guides, a bar fixedly connecting the upper ends of the side walls just within the screen and a stop bar having at its ends a lug-and-socket engagement with the side walls and projecting at its outer edge to overlap the lower bar of the sash to prevent raising of the sash above this part, and manually releasable catches preventing accidental releasing of said bar.

3. A window ventilating device comprising a box-like frame having triangular side walls and adapted to be placed in a window opening against the inner face of the sash, the face of said frame next to the sash having therein a screen and the side walls having screen-receiving guides permitting raising of the screen, a bar fixedly connecting the upper ends of the side walls just within the screen and a stop bar having at its ends a lug-and-socket engagement with the side walls and projecting at its outer edge to overlap the lower bar of the sash to prevent raising of the sash above this part, a spring bar secured by its lower end to the outer face of each of the side walls and having an angle bend at its upper end forming a hook adapted to normally extend over the ends of said stop bar to hold it down.

4. A window ventilating device comprising a frame having triangular side walls, said frame being adapted to be secured in the window opening just inward of the lower sash, said frame having a screen forming its outer vertical face and the side walls having screen receiving grooves permitting raising of the screen, the side walls also each having a groove extending across its upper edge substantially in register with the screen, a stop bar extending over the screen and having lugs extending downward into said grooves in the said upper edge of the side walls, and catches carried by the frame and engaging the ends of the stop bar to prevent its being raised.

Signed at Seattle, King County, Washington, this 14th day of May, 1924.

CHRISTOPHER WILKE.
